D11-160. OR D313 EX

Design No. 313.

Design for Bust of Daniel Webster Patented Sept 17, 1850.

The above is the drawing of the bust of Daniel Webster, now a member of the Senate of the United States from Massachusetts, referred to in my specification of the invention of a new and original design for said bust, dated at Boston on the twenty-fifth day of June A.D. eighteen hundred and fifty. In testimony whereof, the aforesaid subscribers subscribe my name, on said day and year.

Dec. 313

John C. King of Boston, Mass.
Letter, Patent No. 313, dated Sept 17 1850.

The Schedule referred to in these Letters Pat. and making part of the same.

To all persons whom it may concern

Be it known, that I, John C. King,

the undersigned, of Boston in the County of Suffolk, and State of Massachusetts, Sculptor, have invented or produced a new and original design for a bust of Daniel Webster of Massachusetts, now a member of the Senate of the United States from Massachusetts, a drawing of which is hereto annexed.

What I claim as my invention or production is the design of a bust of Daniel Webster as represented in the annexed drawing.

In testimony whereof I, the said John C. King hereto subscribe my name in the presence of the witnesses whose names are hereto subscribed, on the twenty fifth day of June - A. D. 1850 - at said Boston.

Witnesses -

Wm. M. Chase
Henry M. Parker
